UNITED STATES PATENT OFFICE.

HARRY C. PHILLIPS, OF GLOUCESTER, ENGLAND.

ROTARY PUMP.

Application filed June 11, 1923. Serial No. 644,637.

To all whom it may concern:

Be it known that I, HARRY CLARENCE PHILLIPS, a subject of the King of Great Britain, residing at Gloucester, in the county of Gloucester, England, have invented certain new and useful Improvements in Rotary Pumps, of which the following is a specification.

This invention relates to rotary pumps, compressors, prime movers, and the like, of the type comprising a revoluble inner element having a plurality of radial projections and a revoluble investing outer element eccentrically disposed to the inner element, and with recesses or cavities to the extent of one more recess than there are projections on the inner element, with which recesses or cavities the projections sequentially engage, so that opening and closing pockets are formed as the element or elements rotate, whereby there is set up a suction and delivery action on the fluid when the apparatus is driven as a pump or compressor, or into which pockets fluid is admitted for the purpose of driving the apparatus. The present improvements are designed to reduce the capacity of the pockets without altering the speed of the engine, while at the same time maintaining a balance of displacement.

In the present invention, a revoluble inner element is adapted to traverse axially within a revoluble outer element, the displacement so caused being taken up by a movable complementary block of corresponding form or substantially so, to the internal shape of the outer element, whereby the capacity of the pockets is laterally contracted for admission or discharge of fluid.

Referring to the accompanying drawings illustrating a convenient embodiment of my invention,

Fig. 1 is a longitudinal section of a rotary pump or the like constructed according to this invention.

Fig. 2 is a cross section on line A. B. of Fig. 1.

Fig. 3 is a cross section on line C. D. of Fig. 1.

Fig. 4 is a cross section on line E. F. of Fig. 1 on a reduced scale.

Fig. 5 is a longitudinal section in which the inner rotor is supported on a shaft from one side only.

In carrying out the invention with reference to Figs. 1 to 4, the apparatus comprises an inner rotor or element 1 mounted upon

a shaft 2 within an outer rotor or element 3, said rotors or elements being eccentrically disposed to each other and arranged within a casing 4. The inner rotor or element 1 is provided with lobular projections 5 and the outer rotor or element 3 with a series of recesses 6 with which the projections 5 of the inner rotor or element 1 successively engage when rotation of the outer rotor or element 3 takes place.

The inner element 1 is adapted to move axially and is endwise prolonged for a short distance beyond the circumventing outer element 3 in such manner that its projecting part 1^a normally engages a sleeve 7, the inner shape of which corresponds to the shape of the outer periphery of the inner element 1, so that in a sense it constitutes a longitudinal extension of the outer element 3. This sleeve 7 is therefore carried round by the inner element 1 and endwise abuts against the outer element 3. At the opposite side of the apparatus is a complementary block 8 which may be adapted to rotate around an eccentric bush 9 which is freely mounted upon a main shaft 2, said bush enabling the block 8 to run concentric with the outer element 3. The block 8 is formed externally with projections 10 corresponding with the interior shape of the outer element 3 so that it is complementary thereto, and one end of it at 8^a normally engages with the outer element 3, whereby it partakes of the rotary motion of the latter and is always in registration therewith. The block 8 may abut at its inner edge against the adjacent end of the inner element 1. The latter and the block 8 may be moved endwise by means of axially parallel rods 11 acting at opposite ends of the apparatus, one freely abutting against the back of the block 8 and the other abutting against the front face of the inner element 1, said rods being preferably coupled together by means of a connecting rod 12, to which an actuating lever 13 may be connected. It is to be understood, however, that the actuating gear may be substituted by any other suitable mechanism. The casing 4 is provided with a suction or inlet side 14 and a delivery or outlet side 15 communicating with the pockets formed in the recesses 6 between the inner element 1 and the outer element 3.

In the position shown in Fig. 1, the inner element 1 occupies the chamber in the outer element 3 to its maximum extent. If the inner element 1 is now advanced axially into

the sleeve 7, the block 8 is advanced correspondingly into the outer element 3 so that the effective width of the pockets is consequently narrowed and their capacity reduced whereby less fluid is admitted to the pockets, resulting in a corresponding reduction in discharge. This effect is caused without the necessity of altering the speed of the engine. By reason of the block 8 following up the inner element 1, an enlarging space is formed at the back of same within the casing 4, while at the same time a reducing space is formed in the sleeve 7 at the front of the inner element 1. These two spaces intercommunicate and also the pockets formed between the two elements aforesaid by means of pipes or conduits 16, whereby the displacement is compensated.

Fig. 5 shows a slightly modified arrangement of the apparatus, the essential features however being substantially the same. In this construction, the inner rotary element 1 is supported at one end only on a shaft 2^a. Connected to the complementary block 8^b is a guide rod 17 having an enlarged end 18 engaging a recess 19 in said block and being supported at the outer end in a guide bracket 20. Upon the rod 17 is mounted a pointer 21 adapted to move over a scale marked on a rod 22. The spaces within the casing 4 at opposite ends respectively of the inner element 1 and block 8^b and also the recesses or pockets formed between the inner and outer elements 1 and 3 intercommunicate by means of pipes or conduits 23. An auxiliary pump rotor 24 is disposed in the circuit of the pipes 23 so that when the rotor is operated, the movement of the fluid through the pipes 23 is caused to move the inner rotor 1 together with the block 8^b in one or the other direction and to any position so as to increase or decrease the capacity. The fluid is admitted or discharged to or from the end of the inner rotor 1 by way of the annular recess 25 and the ports 26. In the view shown, the block 8^b is almost entirely filling the internal capacity of the outer element 3 so that there is only a small effective space for admission and discharge of the fluid. If the inner rotor 1 and the block 8^b are caused to move to the right, an increasing capacity of the pockets is obtained between the inner and outer elements 1 and 3 and a correspondingly greater inlet and outlet. A pipe 27 may be arranged to connect the space 28 at the back of the rod 17 with the spaced part in the casing 4 at the back of the block 8^b.

What I do claim as my invention, and desire to secure by Letters Patent, is:—

1. A rotary pump, compressor, prime mover, or the like, having in combination a revoluble inner element with a plurality of radial projections, an eccentrically disposed revoluble outer element with exterior pock-

ets, an outer casing for the outer element, said revoluble inner member being adapted to traverse axially of the revoluble outer element, and a complementary block movable correspondingly with the inner element 70 so as to take up displacement, whereby the capacity of the pockets is varied for admission or discharge of fluid.

2. A rotary pump, compressor, prime mover, or the like, having in combination 75 a revoluble inner element with a plurality of radial projections, an eccentrically disposed revoluble outer element with exterior pockets, an outer casing for the outer element, said revoluble inner member being 80 adapted to traverse axially of the revoluble outer element, and a complementary block of corresponding form or substantially so to the internal shape of the outer element and movable therein so as to take up displacement whereby the capacity of the pockets is laterally contracted for admission 85 or discharge of fluid.

3. A rotary pump, compressor, prime mover, or the like, having in combination a 90 revoluble inner element with a plurality of radial projections, an eccentrically disposed revoluble outer element with exterior pockets, an outer casing for the outer element, said revoluble inner member being 95 adapted to traverse axially of the revoluble outer element, and an end-traversable complementary block mounted upon the shaft 100 of the inner element concentrically with the outer element, said block having peripheral projections and recesses corresponding to the internal recesses and projections of the outer element, such that as said block follows up the inner element, it provides a complementary medium occupying the displacement 105 in the outer element.

4. A rotary pump, compressor, prime mover, or the like, having in combination 110 a revoluble inner element with a plurality of radial projections, an eccentrically disposed revoluble outer element with exterior pockets, an outer casing for the outer element, said revoluble inner member being 115 adapted to traverse axially of the revoluble outer element, and a sleeve disposed co-axially and rotatable with the inner element, said sleeve having the same internal configuration or substantially so corresponding to the external configuration 120 of the inner element, whereby it is adapted to receive the inner element as the latter is axially advanced from the outer element.

5. A rotary pump, compressor, prime mover, or the like, having in combination 125 a revoluble inner element with a plurality of radial projections, an eccentrically disposed revoluble outer element with exterior pockets, an outer casing for the outer element, said revoluble inner member being adapted to traverse axially of the revoluble 130

- outer element, a complementary block movable correspondingly with the inner element so as to take up displacement in the outer element, and a bush freely mounted upon the 5 shaft within the complementary block so as to cause the said block to be concentric with the outer element.
6. A rotary pump, compressor, prime mover, or the like, having in combination 10 a revoluble inner element with a plurality of radial projections, an eccentrically disposed revoluble outer element with exterior pockets, an outer casing for the outer element, said revoluble inner member being 15 adapted to traverse axially of the revoluble outer element, a complementary block movable correspondingly with the inner element so as to take up displacement in the outer element, and means providing intercommuni- 20 cation within the casing between the outward end of the inner element, the outward end of the complementary block and the pockets formed between the inner and outer elements.
- 25 7. A rotary pump, compressor, prime mover, or the like, having in combination a revoluble inner element with a plurality of radial projections, an eccentrically disposed revoluble outer element with exterior pockets, an outer casing for the outer element, said revoluble inner member being adapted to traverse axially of the revoluble outer element, a complementary block movable correspondingly with the inner element 30 so as to take up displacement, and means for axially moving the inner element and complementary block together for varying the capacity of the pockets between the inner and outer elements.
- 35 8. A rotary pump, compressor, prime mover, or the like, having in combination a revoluble inner element with a plurality of radial projections, an eccentrically disposed revoluble outer element with exterior pockets, an outer casing for the outer element, said revoluble inner member being adapted to traverse axially of the revoluble outer element, a complementary block mov- 40
- able correspondingly with the inner element so as to take up displacement, and a guide rod 50 upon the complementary block, said guide rod having a pointer adapted to move over a scale or marking for registering the position of the block in the outer element.
9. A rotary pump, compressor, prime mover, or the like, having in combination a revoluble inner element with a plurality of radial projections, an eccentrically disposed revoluble outer element with exterior pockets, an outer casing for the outer 60 element, said revoluble inner member being adapted to traverse axially of the revoluble outer element, a complementary block movable correspondingly with the inner element so as to take up displacement, a guide rod con- 65 nected to the complementary block, and a hollow guide bracket for the guide rod, the space of said bracket communicating by means of a conduit with the space within the casing at the back of the complementary 70 block.
10. A rotary pump, compressor, prime mover, or the like, having in combination 75 a revoluble inner element with a plurality of radial projections, an eccentrically disposed revoluble outer element with exterior pockets, an outer casing for the outer element, said revoluble inner member being adapted to traverse axially of the revoluble outer element, a complementary block movable correspondingly with the inner element 80 so as to take up displacement, conduits affording communication in the casing between the outward end of the inner element, the outward end of the complementary block and 85 the pockets between the inner and outer elements, and an auxiliary pump rotor disposed in the circuit of the conduits so that axial movement is imparted to the inner element and complementary block in either 90 direction to increase or decrease the capacity.

In testimony whereof I affix my signature.

HARRY C. PHILLIPS.
